UNITED STATES PATENT OFFICE.

ARNETT WILSON, OF YOUNGSTOWN, OHIO.

AVIATION HARNESS.

Application filed March 11, 1922. Serial No. 543,128.

To all whom it may concern:

Be it known that I, ARNETT WILSON, a citizen of the United States, residing at Youngstown, in the county of Mahoning and State of Ohio, have invented certain new and useful Improvements in Aviation Harness, of which the following is a specification, reference being had to the accompanying drawings.

10 This invention relates to aviation harness, and more particularly to a harness to be worn by an aviator and providing means for attaching a parachute.

15 An important object of the invention is to provide a harness of this character which may be worn in conjunction with the ordinary aviation clothing and which will permit the removal of the aviation clothing by the aviator during descent by parachute if so desired.

20 A still further object of the invention is to provide a harness of this character embodying a detachable cork belt which may be attached when a descent in the proximity 25 of a body of water becomes necessary.

25 A still further object of the invention is to provide a harness of this character which is simple in its construction, strong and durable in service, and a general improvement 30 in the art.

These and other objects I attain by the construction and arrangement shown in the accompanying drawings wherein for the purpose of illustration is shown a preferred 35 embodiment of my invention and wherein like reference characters designate like parts throughout.

In the drawings:

Figure 1 is a front elevation of a harness 40 constructed in accordance with my invention;

Figure 2 is a rear elevation thereof;

Figure 3 is a detail sectional view showing the manner of attaching the crotch strap 45 to the belt; and

Figure 4 is a detail view showing the ring and loop of the crotch strap.

Referring now more particularly to the drawings, the numeral 10 indicates the body 50 portion of the harness which is provided with arm openings 11 and leg openings 12. The body portion is provided at its edges with detachable securing elements whereby it may be fastened about the body, as indicated at 13, these securing elements prefer-

ably taking the form of straps and buckles. Auxiliary securing elements such as button and eyelet, indicated at 13^a, may be employed if so desired for closing the flap. With the flap closed, a neck opening 14 is 60 provided.

The body portion is provided at the waist line thereof with keepers 15 in which is mounted a broad leather belt 16 having a separable connection at the front, as indicated 65 at 17, preferably in the form of a buckle attachment. To the belt 16, approximately centrally of the back portion thereof, is secured, as at 18, a strap 19 of suitable width, the form of the attachment being preferably 70 a loop 20 formed upon the end of the strap 19 through which the belt 16 extends, securing elements or stitching extending through the sections of the loop and the belt 16. This strap passes down beneath the crotch portion 75 of the harness and upwardly at the front and is provided at its free end with a loop 21 in which is permanently secured a ring 22 for the reception of the snap hook 23 of a 80 parachute. Through this loop 21 and the ring 22 the belt 16 is directed in securing the same so that the ring not only engages the strap 19 but the belt 16 as well. The harness preferably likewise includes keepers 24 through which may be directed a cork or 85 other float belt 25, the free ends of which are secured by separable fasteners, as at 26, so that the belt 25 may be removed and stowed at some convenient point until its use becomes necessary.

Attention is directed to the fact that the peculiar construction of the harness permits its use with the ordinary aviator's suit which usually includes a pair of fur lined pants having integral feet portions in which the feet of the aviator are disposed, and a leather coat. By employing the construction shown, when the aviator is forced to descend upon and alight in a body of water, the pants and coat of the the aviation suit 95 may be removed during the parachute drop, thereby affording greater freedom of movement and eliminating a great deal of unnecessary weight. Attention is further directed to the fact that the attaching ring 22 is disposed at the front of the harness permitting detachment of the parachute after landing. This is particularly advantageous where such landings are made in water, as the wind catching in the parachute will often 100 105 110

drag the aviator, causing death by drowning.

From the foregoing it is believed to be obvious that a harness constructed in accordance with my invention is particularly advantageous in that it may be worn with the ordinary aviation clothing now employed and in that it may be readily attached and detached from a parachute, the harness being furthermore very easily applied. It will furthermore be obvious that the construction of the harness may be altered somewhat from the construction hereinbefore set forth without materially departing from the spirit of my invention and I accordingly do not limit myself to the peculiar construction thereof except as hereinafter claimed.

I claim:

- 20 1. In an aviation harness, a close fitting body garment devoid of arm and leg portions, a belt carried by the body portion and having a strap secured thereto at the center of the back portion therof, a detachable connection for the ends of the belt, a loop formed upon the free end of the strap, and a ring carried by the loop, the free ends of said belt being connected through said loop and ring.
- 25 2. In an aviation harness, a body harness including a belt and a crotch strap permanently secured to the belt at one end and adapted to be disposed between the legs of the wearer and having portions through which the belt may extend at its free end, and a ring through which said crotch strap and belt pass and adapted for engagement with a supporting hook.
- 30 3. In an aviation harness, a close fitting body garment devoid of arm and leg portions, a row of keepers disposed centrally

to the body portion, a belt mounted in the keepers, a detachable connection for the ends of the belt disposed at the front of the garment, a crotch strap secured to the belt at the center of the rear portion thereof and adapted to be passed between the legs of the wearer provided with a loop receiving the belt, and a hook ring through which the belt and crotch strap pass.

4. In an aviation harness, a close fitting body garment devoid of arm and leg portions, a row of keepers disposed centrally to the body portion, a belt mounted in the keepers, a detachable connection for the ends of the belt disposed at the front of the garment, a crotch strap secured to the belt at the center of the rear portion thereof and adapted to be passed between the legs of the wearer and provided with a loop receiving the belt, a hook ring through which the belt and crotch strap pass, and means for detachably connecting a float belt to such harness.

5. In an aviation harness, a close fitting body garment devoid of arm and leg portions divided centrally of the front thereof from top to bottom, means for securing the edges of the garment together, keepers carried by the garment and disposed in a row centrally thereof, a belt disposed in the keepers, a crotch strap having a loop receiving the belt at the rear of the garment and adapted to pass between the legs of the wearer, said crotch strap being provided at its free end with a loop, and a ring disposed within the loop, said belt being connectible through said ring and loop.

In testimony whereof I hereunto affix my signature.

ARNETT WILSON.
